(57) CLAIM

The ornamental design for a pair of grille lights for a vehicle, as shown and described.

DESCRIPTION

FIG. 1 is a perspective view of a pair of grille lights for a vehicle, showing our new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left elevation view thereof; and,

FIG. 7 is a right elevation view thereof.

The broken lines in the drawings illustrate portions of the pair of grille lights for a vehicle that form no part of the claimed design.

The claim is directed to the collective appearance of the articles shown in FIGS. 1-7.

1 Claim, 4 Drawing Sheets
